DISCARD DISPOSAL MEANS FOR METAL
EXTRUSION PRESSES

Peter Billen, Leverkusen, Germany, assignor to The Loewy Engineering Company Limited, Bournemouth, England, a company of Great Britain
Filed July 26, 1963, Ser. No. 297,893
8 Claims. (Cl. 207—1)

This invention relates to the extrusion of metal billets in presses, and particularly to that stage of an extrusion operation which is concerned with the disposal of the unextruded portion of a billet, the billet discard. The separation of the discard from the extruded articles and the subsequent removal of the discard from the press are unproductive steps in the cycle of operation of an extrusion press; it is therefore desirable that they should be carried out as expeditiously as possible.

In many presses, especially in presses for the extrusion of tubular articles, the separation of the discard from an extruded article is effected by means of a punch with a cutting edge at its front end. This punch is normally kept in a parked position away from the extrusion axis, and moved into this axis only for discard-shearing purposes. In the latter position, the punch is advanced towards the extrusion die by hydraulic power either through a separate ram or through the main ram of the press, and is thus rendered effective for separating the discard from the extruded article at the face of the die. After shearing, the punch is retracted with the discard impaled thereon; the discard is taken off and the punch moved back to its parked position.

It is an object of the present invention to provide in a metal extrusion press an improved arrangement in which a piece of discard, impaled on a punch after a shearing operation, can be disposed of in a more expeditious manner than was heretofore the case.

One embodiment of the invention will now be described by way of example with reference to the accompanying drawings, in which:

FIG. 1 is a transverse view of part of an extrusion press into which the invention has been incorporated, showing the arrangement of the discard-shearing means in the press.

FIG. 2 is a section through part of the press of FIG. 1 along the line A—A of FIG. 1.

FIG. 3 is an enlarged sectional view of a discard-shearing unit, incorporated into the press of FIGS. 1 and 2, shown immediately before discard-shearing.

FIG. 4 is a view similar to that of FIG. 3, showing the unit during discard-shearing.

FIG. 5 is a view similar to FIG. 3, showing the unit after discard-shearing but still in the extrusion axis.

FIG. 6 shows the unit in the parked position away from the extrusion axis during the transfer of the discard.

FIG. 7 is a view similar to that of FIG. 6, showing the parts after the disposal of the discard.

The press shown in FIGS. 1 and 2 is of the type in which a plurality of die assemblies and a plurality of containers are mounted on two separate rotary carriers so that die assemblies and containers mounted thereon can be moved in succession from a working station in the extrusion axis into a parking station away from this axis, and back. The press has a platen 10 which is connected by four columns 12 to a main cylinder, not shown. A die-assembly carrier in the form of a spider wheel 14 is rotatably mounted on one of the columns, and a container-carrier in the form of a turntable 16 is rotatably mounted on another column, the two columns being situated diametrically opposite each other with regard to the extrusion axis X—X as shown in FIG. 1.

The spider wheel 14 has two pairs of diametrically opposite arms 20 of which one pair carries two die assemblies 18. Supported on the turntable 16 are two billet containers 22 and two discard-shearing units 24. The 5 containers and the discard-shearing units respectively are arranged diametrically opposite to each other with regard to the axis of rotation of the turntable. Rotation of the turntable 16 by 90° moves alternately a container 22 or a discard-shearing unit 24 into the extrusion axis X—X.

In the example shown, each die-assembly 18 comprises two backing plates 26 arranged one behind the other and in line with an extrusion die 28 which is loosely inserted into the bore of a container 22. A die bolster 30 is attached to the platen 10. Further arranged in the extrusion axis X—X is a pressing stem 32 and a mandrel 34 which can be retracted into the stem. A pressing disc 36 is secured to the stem.

The parts described co-operate with each other during an extrusion cycle in the well-known manner. A billet is first placed into the bore of that container 22 which is in the extrusion axis X—X. This billet may be hollow, or, if solid, may be pierced by the advancing mandrel 34. Further advance places the tip of the mandrel in the extrusion die 28 whereupon the pressing stem 32 enters the container bore and extrudes the billet through the annular opening between mandrel 34 and die 28 so as to form a tube T. The end of the billet cannot be extruded for well-known reasons and remains joined to the extruded tube T in the form of a discard D. This discard has to be severed from the tube before the latter can be withdrawn from the press. To this end, one of the two discard-shearing units 24 is moved into the extrusion axis in the place of a container 22, the exchange being effected by rotation of the turntable 16. The arrangement of discard-shearing units and containers on the same carrier forms the subject of the co-pending patent application No. 207,717, filed July 5, 1962.

Each discard-shearing unit 24 consists, as shown in FIG. 3, of a punch 40 which has a head 42, a neck 44 and a foot 46. The foot is seated in the recess 48 of a socket 50 which forms part of a barrel 52. The latter is slidable in the longitudinal direction of the punch in a sleeve 54 having an inner flange or rim 56. The sleeve 54 is axially slidable in a holder 58 secured to the turntable 16 by a retaining ring 60. A spring 62 is inserted between the barrel 52 and the sleeve 54 and a spring 64 is inserted between the inner sleeve 54 and the holder 58. The springs 62 and 64 are held in their respective positions by rings attached to the barrel 52 and the sleeve 54 and the holder 58 respectively.

A discard-shearing unit 24 comprising a punch 40, the sleeve 54 and the holder 58 and the two springs 62 and 64 can be positioned into a carrier 16 and withdrawn therefrom as a unit.

As seen in FIG. 1, one of the discard-shearing units 24 when in its parked position is situated below the extrusion axis X—X. This is the position which the unit assumes after a discard has been sheared off and the turntable 16 rotated by one step of 90° thereafter. Arranged below the extrusion axis X—X and so that a parked unit 24 is in alignment therewith are discard-holding means in the form of a finger 66 which can be moved by a ram displaceable in a cylinder 68. The finger 66 is guided in a tubular bracket 70 to which a stationary stripper plate 72 is attached. The finger 66 faces the punch 40 when the latter is in the parked position and is in alignment with the punch.

After an extrusion operation has been performed, the 70 turntable 16 and the wheel 14 are separated from each other in the axial direction by moving one of these two parts or both. The loose die 18, being sandwiched be-

tween the discard D and the first backing plate 26, adheres to the discard and is pulled out of the container bore, together with the discard upon separation of container and die-assembly. The turntable 16 is then rotated by one step of 90°, and a discard-shearing unit 24 is moved into the extrusion axis X—X taking the place of the container. The parts are then in the position shown in FIG. 3.

The pressing stem 32 with the pressing disc 36 attached thereto is now advanced to the left, and after having become seated in a conical recess in the barrel 52 advances the barrel and the punch 40 to the left and into the position of FIG. 4. The cutting edge provided between the head 42 and the neck 44 of the punch, severs the discard D from the extruded tube T which can now be withdrawn from the press (FIG. 5). Discard D and die 28 form together a clump which is impaled on the punch. The sleeve 54 advances together with the barrel 52 and the punch 40, because the front end of the barrel 52 abuts against the inner flange 56. The pressing stem 32 and the pressing disc 36 are now retracted and the punch 40 with the barrel 52 and the sleeve 54 are free to return to their respective starting positions shown in FIG. 3, under the action of spring 64.

The turntable 26 is rotated again, so that a fresh container 22 is moved into the extrusion axis X—X, and the discard-shearing unit 24 is moved into the parking station below the extrusion axis. In this position, the unit is in alignment with the finger 66. The finger is advanced by the ram in the cylinder 68 and pushes the punch 40, together with its barrel 52, backwards without moving the sleeve 54. The flange 56 acts as a stripper and assists in the transfer of the clump from the punch to the finger, as shown in FIG. 6. The latter is then retracted with the clump impaled thereon. In the course of this movement, the clump abuts against the plate 72 which removes the clump from the finger so that it drops into a chute 74 (FIG. 1) at the bottom of the press for further disposal. The punch 40 is returned by the spring 62.

It will be understood that while the discard-shearing unit 24 is in its parked position and the clump is stripped off the finger, a container 22 has arrived in the extrusion axis, and preparations for the next extrusion can be made without having to wait for the removal of the discard from the punch.

In the above description, it has been assumed that the die adheres to the discard after shearing and forms a clump therewith, impaled first on the punch and then on the finger. It is clear that the invention is equally applicable to presses in which the die stays apart from the

discard or the pressing disc is included in the impaled clump.

What I claim is:

5 1. In a metal extrusion press, an extrusion die, means for shearing a piece of billet-discard remaining on the face of said die from an extruded article, said means comprising a punch on which the piece of discard is impaled after shearing, said punch being movable from a discard-shearing position in the extrusion axis to a parking position outside the extrusion axis, discard-holding means which face the punch when the latter is in the parking position, and means for transferring the piece of discard from the punch to said discard-holding means.

10 2. A metal extrusion press according to claim 1, in which said holding means consist of a finger which is aligned with said punch when the latter is in the parking position, and means for moving said finger on transference to said finger.

15 3. A metal extrusion press according to claim 2, having stripping means assisting in the transfer of said piece of discard from said punch to said finger.

20 4. A metal extrusion press according to claim 3, having further stripping means for removing said piece of discard from said finger upon its retraction from said punch.

25 5. A metal extrusion press according to claim 2, having a carrier for said discard-shearing means, said carrier being movable relative to the press axis, a sleeve guided in said carrier, said punch being slidably guided in said sleeve, stripping means for the transfer of the piece of discard from said punch to said finger being attached to said sleeve, and means ensuring movement of said sleeve together with said punch during discard-shearing only.

30 6. A metal extrusion press according to claim 5, having first spring means urging said sleeve in one direction relative to said carrier, and second spring means urging said punch in the opposite direction relative to said sleeve.

35 7. A metal extrusion press according to claim 1, having a carrier for said discard-shearing means, said carrier being movable relative to said press axis, and a billet-container mounted on said carrier, said discard-shearing means and said container being adapted to exchange positions in the press axis upon movement of said carrier.

40 8. A metal extrusion press according to claim 7, in which said carrier is rotatable about an axis parallel to the press axis.
